UNITED STATES PATENT OFFICE.

ISAAC M. HICKMAN, OF SPRINGFIELD, AND FRED H. LYNCH, OF LEBANON, MISSOURI,
LENA HICKMAN, ADMINISTRATRIX OF SAID ISAAC M. HICKMAN, DECEASED, AS-
SIGNORS TO J. E. ROBERTS AND GUS BENNERT, BOTH OF SPRINGFIELD, MISSOURI.

CHURN.

1,115,935.

Specification of Letters Patent.

Patented Nov. 3, 1914.

Application filed April 7, 1913, Serial No. 759,565. Renewed September 12, 1914. Serial No. 861,487.

To all whom it may concern:

Be it known that we, ISAAC M. HICKMAN and FRED H. LYNCH, citizens of the United States, residing at Springfield and Lebanon, respectively, in the counties of Greene and Laclede, respectively, State of Missouri, have invented certain new and useful Improvements in Churns, of which the following is a specification, reference being had 10 to the accompanying drawings.

This invention relates to new and useful improvements in churns, and more particularly to an improved dasher therefor.

An object of this invention is the provision 15 of a dasher and means for readily supporting the same within the churn.

A further object of this invention is the provision in combination with a churn of a dasher, which will be comparatively simple 20 and inexpensive to manufacture, reliable and efficient in use, and which can be quickly secured within the churn, or removed therefrom for cleaning purposes.

With the above and other objects in view, 25 this invention resides in certain novel features of construction, formations, combinations and arrangements of parts to be hereinafter more particularly described, claimed and illustrated in the accompanying drawings, in which—

Figure 1, is a vertical sectional view of our invention. Fig. 2, is a horizontal sectional view thereof.

The following invention is designed for 35 the purpose of improving Letters Patent, No. 830,010, by supplying an improved dasher therefor.

Referring to the accompanying drawings by similar characters of reference, the number 40 10 designates generally the churn which consists of a substantially cylindrical receptacle 11 having a removable top or closure 12. This receptacle 11 is mounted in the frame 12 supported by the springs 45 13, as clearly shown, for obvious reasons.

The cover 12 is provided at diametrically opposite points adjacent its outer edge with threaded openings 14. These openings extend from the inner side of the closure 12 to

a point adjacent the opposite side thereof 50 thus making a solid outer surface which will prevent leakage. A pair of depending rods 15 having upper screw threaded terminal shanks 16 are threaded in the openings 14, being limited in their movement by the 55 collars 17 formed upon the said rods. The lower terminals of the rods 15 are likewise provided with screw threaded shanks 18 which shanks are adapted to extend through the openings 19 formed in the opposite ends 60 of a dasher 20 disposed within the receptacle 11 substantially intermediate the ends thereof. This dasher is retained upon the rods 15 by means of the winged locking nuts 21. The dasher 20 can be of any desired shape 65 or size but is preferably made slightly less in width and length than the diameter of the receptacle 11 in order that the contents thereof can pass through its opposite sides. The dasher 20 is further provided with 70 spaced openings 21 through which the contents of the receptacle can also pass. The locking nuts 21 afford a means for quickly removing the dasher from the rods 15 after the cover 12 has been removed from the 75 receptacle, for cleaning purposes, and if desired the rods 15 can also be unscrewed from the openings 14 by rotating them in a proper direction. The collars 17 formed upon the rods 15 prevent the contents of 80 the receptacle 11 from working its way into the openings 14 between the threads of the said openings and shanks 16.

From the foregoing disclosures taken in connection with the accompanying drawings, it will be manifest that a dasher for churns is provided which will fulfil all of the necessary requirements of such a device. It should be understood in this connection that various minor changes in the specific 90 details of construction can be resorted to within the scope of the appended claim, without departing from or sacrificing any of the advantages of the invention.

Having thus fully described this invention what we claim as new and desire to protect by Letters Patent is:

In a churn, the combination of a churn

body, a cover secured to said body, means for retaining the cover in position, a pair of depending rods threaded in the under face of the cover, a flat dasher having its opposite ends mounted on the rods and provided with central openings, means for preventing the dasher from working off of the lower ends of the rods, and resilient supporting means for the churn

In testimony whereof, we hereunto affix to our signatures in the presence of witnesses.

ISAAC M. HICKMAN.
FRED H. LYNCH.
